Term of patent 14 years

Int. Cl. D9—05

U.S. Cl. D9—249

FIG. 1

FIG. 2

FIG. 1 is a perspective view of a shopping bag in partially open position; and

FIG. 2 is an end elevational view.

The bottom of the shopping bag is substantially plain and unornamented. The walls not shown are identical to those shown in the drawings.

The characteristic feature of the design resides in the shopping bag shown comprising a top border decoration having a series of stripes therein of graduated width ranging from a relatively wide top stripe to a narrow bottom stripe.

I claim:

The ornamental design for a shopping bag, as shown and described.
